(57) **CLAIM**

The ornamental design for a windshield wiper arm and blade, as shown and described.

DESCRIPTION

FIG. 1 is a perspective view of a windshield wiper arm and blade showing our new design;

FIG. 2 is a top plan view thereof shown on a reduced side;

FIG. 3 is a bottom plan view thereof;

FIG. 4 is a front elevation thereof; and,

FIG. 5 is a rear elevation thereof.

In FIG. 3, the broken lines identify the boundary of the claimed design but forms no part of the claimed design.

In FIGS. 4 and 5, the broken lines show portions of the wiper arm design but form no part of the claimed design.

1 Claim, 5 Drawing Sheets
